MECHANISM FOR PRECISION SWITCHES

Edwin August Miller, Fairfield, Conn.

Application March 16, 1945, Serial No. 583,049

5 Claims. (Cl. 200—67)

1

This invention relates to mechanism for precision switches, including switches adapted for alternate electric circuits.

The objects of the invention are to provide a snap action switch which maintains a constant maximum contact pressure up to the breaking point; to provide a switch having an actuating means including a flat spring material to which resilient properties are imparted while a portion of the material is held in a predetermined manner; and to provide a switch the mechanism of which is compact, with the least required exertive pressure of operation, and adapted for a reduced arc of oscillation.

Referring to the accompanying drawing, the Figure 1 is an erect elevation of the device, illustrating its insulation casing in cross-section and its mechanism in a maintained at-rest position; Figure 2 is a similar elevation but illustrating its mechanism in an operated position; Figure 3 is a top surface view of the oscillating member; Figure 4 is a perspective view of the link member; Figure 5 is a perspective view of the leaf spring member; and the Figures 6 and 7 are diagrammatic layouts of two mechanical positions of the oscillating member and associated parts.

With more particular reference to the accompanying drawing, there is illustrated one form only of the invention with regard to the novel mechanism and manner by which the improvement herein set forth is achieved. Other forms within the scope of the invention may be obvious.

The casing 1, of insulation material, illustrated in cross-section, accessibly provides wire connection terminals 2, 3 and 4 adapted for electric wiring (not illustrated) for the establishment of separate alternate circuits within which the switch may be inserted. The inner extremities of terminals 2 and 3 provide the spacedly aligned fixed contacts 5 and 6 rigid with said casing 1. The sheet-metal oscillating body member 7, one end of which is anchored, as at 8, within the casing 1 where it is provided with a permanent connection with the inner end of the terminal 4, as illustrated by the Figures 1 and 2, carries at its opposite end the upper and lower superposed contact surfaces 9 and 10, respectively, adapted for alternate engagements with the fixed contacts 5 and 6 in maintained at-rest and operated positions of the oscillating body member 7. The tongue 11 is illustrated as integral with the body member 7 and pendulously formed by being cut on three sides from within the central surface-length thereof, the extremity of the tongue 11 being shortened, as at 11B, leaving unoccupied a portion of the tongue operating space 7A. The tongue 7 however, is extended by means of the link 12 of which one end edge is turned downwardly, as at 13, and at the opposite end edge is provided with the extended lugs 13A, the turned portion 13 being provided at its side edges with open marginal recesses 14 into which fit the

2

extended lugs 11A provided by the free extremity of the shortened tongue 11 as a convenient means of hinged assembly of the link 12 therewith. The thin leaf spring 15 at its upper end is secured to the insulation casing 1 and the free lower end is movably held within the slot 16 of the casing 1. Said leaf spring 15 is provided at its side edges with the open recess 17 within which fit the extended lugs 13A of the link 12 as a means of hinged assembly. The tension of the leaf spring 15 is exerted outwardly against the link 12 in one direction only, the link 12 thus being held at a slight angle with the inclined edge of the tongue 11 and thus maintained by means of the coil spring 18, having a support rigid with the casing 1. The hinged assemblies make possible an increased sensitivity of operating pressure.

As illustrated by the Figure 1, the oscillating body member 7 and connected parts of the precision switch mechanism are held at-rest in an over-centered position by means of said coil springs 18. In the Figure 2, the mechanized parts are illustrated as having been operated by means of manual pressure by the thumb 19 placed upon the push element 20 whereby the link 12, together with the tongue 11 at the point of their hinged connection, is depressed against the tension of the coil spring 18, thereby operating the tongue 11 from its over-centered position relative to the oscillating body member 7 to an under-centered position.

Due to the over-all length of the combined tongue 11, link 12 and connected leaf spring 15, within their operating open space 7A, being slightly greater than the entire opening 7A, the tongue 11, depressed by pressure upon the link 12 hinged therewith is forced to a relatively flexed condition with regard to the oscillating body member 7. In such forced movement from the over-centered position, through a center to an under-centered position of the tongue 11 and link 12 at their point of hinged connection, the body member 7 is sufficiently distorted so that the transition is one of sudden snap action wherein in the free end of the oscillating body member 7, carrying the superposed contacts 9 and 10, engages its contact 9 with the fixed contact 5, rigid with the casing 1, which contact engagement is maintained against the tension of the coil spring 18 as long as manual pressure remains upon the push element 20, as illustrated by the Figures 2 and 7. With the release of such manual pressure, the coil spring 18 acts to reverse the operation of the mechanical parts with the same sudden snap-action as when manually operated. In such reversal of action however the tongue 11 at the hinged connection of the link 12 passes back through center to its normally maintained over-centered position, again returning the engagement of the contact 10 with the fixed contact 6 rigid with the casing 1, as illustrated by the Figures 1 and 6, the engage-

ment being augmented by means of the coil spring 18.

While manual pressure is herein illustrated as means by which the precision switch is operated to one of its extreme positions, it is to be understood that such movement of operation is adapted to be accomplished by any other means, such as when the invention is employed as a part of an automatic means adapted for precision control in mass production of an article, in which case the switch may be mechanically operated as a part of such means.

In the Figures 6 and 7, it will be noted that the full line 7 designates the body of the oscillating member, and the dotted line 11 represents the tongue member. In the Figure 6 the tongue 11, at its end connected with the link 12, is shown over-centered with relation to the body of the oscillating member 7 while, in the Figure 7 the tongue 11 at said end is shown under-centered with relation to said body 7, such positions of the tongue 11 determine engagements of the contacts 9 and 10 carried by the body member 7 relative to the fixed contacts 5 and 6.

The novel introduction herein of the hinged link 12 as an extension of the tongue 11, makes it possible to build said switch mechanism within a short and more compact casing; for a length of a tongue equal to the combined short length of the tongue 11 and link 12 would tend to add stiffness and thus increase the required exertive pressure of operation. The hinged assembly, as employed by said mechanism, allows a greater differential movement as between the push element 20 and the travel of the oscillating member 7 between the fixed contacts 5 and 6.

I claim:

1. A snap-acting control mechanism for a precision switch comprising an oscillating body member having one end fixed to a supporting base and carrying at the free end contact surfaces for alternate engagements with relatively fixed contacts rigid with said base, said body member having a central elongated opening therethrough; a tongue secured at one end to said body member within said opening; a leaf spring supported by said base within said opening adjacent the free end of said tongue and exerting its tension outwardly along the plane of said opening; a link member interposed between said spring and said tongue; a hinged connection between said leaf spring and said link and between the link and the free extremity of said tongue, the connected tongue, link and spring requiring a length of space greater than that of said opening, the said tongue is normally flexed to an over-centering position with respect to said body member thus distorted and engaging one of its contact surfaces with one of the fixed contacts; operating means to move said link, and hence the free end of said tongue with a snap-action from said over-centering position, through a center and to an under-centering position to release said contact engagement and to engage the other contact surface with the other of said fixed contacts; and means for effecting the return movement of the oscillating member.

2. A snap-acting control mechanism for a precision switch comprising an oscillating body member having one end fixed to a supporting base and carrying at the free end contact surfaces for alternate engagements with relatively fixed contacts rigid with said base, said body member having a central elongated opening therethrough; a tongue secured at one end to

said body member within said opening; a leaf spring supported by said base within said opening remote from said contact surfaces and exerting its tension outwardly along the plane of said opening; a link member within said opening and having hinged connections with the free end of said tongue and with said leaf spring, the connected tongue, link and spring requiring a length of space greater than that of said opening, the said tongue is normally flexed to an over-centering position with respect to said body member thus distorted and engaging one of its contact surfaces with one of the fixed contacts; manual means for operating said link, and hence said connected tongue with a snap-acting movement from said over-centering position, through a center and to an under-centering position to release said contact engagement and engage the other contact surface with the other of said fixed contacts; and separate spring means to effect the return movement of the oscillating member.

3. An oscillating member for a snap-acting control of a precision switch, said member comprising a sheet-metal body of which one end is secured to a base and the opposite end is provided with contact surfaces, said body having an elongated opening therethrough; a tongue within a portion of said opening and secured at one end of said body; a spring supported by said base within said opening remote from said contact surfaces; a link member interposed between the free end of said tongue and said spring; and hinged connections of said tongue, link and spring in such manner that their overall length is greater than that of said opening.

4. An oscillating member for a snap-acting control of a precision switch, said member comprising a sheet-metal body of which one end is secured to a base and the opposite end is provided with contact surfaces, said body having an elongated opening therethrough; a tongue within a portion of said opening and secured at one end of said body; a leaf spring supported by said base within said opening remote from said contact surfaces and exerting a tension in one direction; a link member interposed between the free end of said tongue and said spring; and a hinged connection of said tongue, link and spring in such manner that their overall length is greater than that of said opening.

5. An oscillating member for a snap-acting control mechanism for a precision switch, said member comprising a sheet-metal body of which one end is supported by a base and the other end provided with contact surfaces; a tongue secured at one end to said body member; a spring supported by said base remote from said contact surfaces; a link interposed between said tongue and said spring; and a hinged connection of said link with said spring and the free end of said tongue, the overall length of the connected tongue, link and spring being greater than the space between the place of securement of said tongue to said body member and the supporting base of said spring.
